UNITED STATES PATENT OFFICE

FREDERICK DINGER, OF NEW YORK, N. Y.

DESIGN FOR A FINGER RING

Application filed April 21, 1931. Serial No. 39,582. Term of patent 14 years.

To all whom it may concern:

Be it known that I, FREDERICK DINGER, a citizen of the United States, and a resident of the city of New York borough of Manhattan, in the county of New York and State of New York, have invented the new, original, and ornamental Design for Finger Rings, of which the following is a specification.

Reference is had to the accompanying drawings, forming a part of this specification, in which—

Figure 1 is a perspective view of a finger ring showing my new design;

Figure 2 is a plan view illustrating both shanks of the ring as they would appear when laid flat.

I claim:

The ornamental design for a finger ring, substantially as shown.

FREDERICK DINGER.
